L. F. FRASER

DRILLING DEVICE

Filed April 28, 1924

O. Thalmann

WITNESS:

L. F. Fraser
INVENTOR
BY *Victor J. Evans*
ATTORNEY

UNITED STATES PATENT OFFICE.

LOVIAS FAIRY FRASER, OF DRUMRIGHT, OKLAHOMA.

DRILLING DEVICE.

Application filed April 28, 1924. Serial No. 709,597.

To all whom it may concern:

Be it known that I, LOVIAS F. FRASER, a citizen of the United States, residing at Drumright, in the county of Creek and State 5 of Oklahoma, have invented new and useful Improvements in Drilling Devices, of which the following is a specification.

This invention relates to walking beams of the character used in oil fields, and contains 10 templates a structure possessing greater strength and durability than those in present day use, and one wherein the beam can be adjusted laterally with respect to its support.

15 The nature and advantages of the invention will be better understood when the following detailed description is read in connection with the accompanying drawing, the invention residing in the construction, combination and arrangement of parts as claimed.

20 In the drawings forming part of this application, like numerals of reference indicate similar parts in the several views, and 25 wherein;

Figure 1 is a top plan view.

Figure 2 is a side elevation.

Figure 3 is an end elevation.

Referring to the drawings in detail, 30 represents the Sampson post of the supporting structure which is preferably formed of piping, and provided with a flange 11 which reposes upon a concrete base or foundation 12 as clearly shown in Figure 2. The upper 35 end of this post is received by a casting 13 which is formed with lateral projecting apertured lugs 14, the lugs receiving stay rods 15 which pass downwardly at opposite sides of the post 10, through openings in the 40 flange 11, and have their lower extremities embedded in the concrete foundation 12. In addition to the lugs 14 this casting is also provided with a web 16 which supports a transverse bolt 17, and terminally connected 45 with the ends of this bolt are the adjacent extremities of adjustable truss rods 18. These rods 18 are arranged in convergent relation and have their lower ends embedded in the concrete blocks 19 which are arranged 50 at opposite sides of the concrete foundation 12. The casting 13 is as clearly illustrated in Figure 3 provided with a substantially U-shaped portion 20 which forms a bearing for the trunnions 21 which project laterally 55 from the lower part 22 of a clamp, the upper or cooperating part of which is indicated at

23. The part 23 is bolted or otherwise suitably secured to the part 22 as clearly illustrated in Figure 2. The walking beam formed from an appropriate length of casting or pipe is indicated at 24, and is received by the clamp just described, which allows this beam to be adjusted laterally with respect to its support, as well as rocked upon the trunnions 21 carried by the clamp. Rising 60 from the upper part 23 of the clamp is a plate 25 having obliquely disposed openings 26 to receive the adjacent ends of the truss rods 27, these rods being extended outwardly and downwardly to their point of connection with the beam 24, or in other words connected with this beam at opposite sides thereof and at points adjacent the free ends of the beam. The beam is provided with apertured lugs 28 to receive the ends of these 65 rods. It is manifest, from the general construction and arrangement of parts, that I have devised a walking beam and support therefor which possesses maximum strength, and durability, and one wherein the beam 70 can be conveniently adjusted laterally by simply loosening the clamp above described.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

1. In combination, a base, a post rising therefrom, a U-shaped bearing supported by the post, a two part clamp pivoted in said 95 bearings, a tubular beam slidable within the clamp for lateral adjustment with respect to the post, and stay rods terminally connected with the post and ground.

2. In combination, a base, a post secured thereto and rising therefrom, a U-shaped bearing supported by the post, a two part clamp, trunnions projecting from one part of the clamp and pivoted in said bearings, a tubular beam supported by said clamp and capable of lateral adjustment with relation to the post, a plate rising from said clamp in alignment with said post, and truss rods terminally connected with the plate and the ends of said beam.

3. In combination, a base, a post rising therefrom, a casting supported on the post,

and including a substantially U-shaped bearing, apertured lugs projecting from the casting, stay rods passed through said lugs and connected with the base for holding the post positioned thereon, a two part clamp, trunnions projecting from one part of the clamp and pivoted on said bearing, a tubular beam received by and supported by said

clamp and capable of lateral adjustment with relation to the post, a plate rising from the other part of the clamp and disposed in alignment with said post, and truss rods terminally connected with the plate with said beam adjacent the free ends thereof.

In testimony whereof I affix my signature.
LOVIAS FAIRY FRASER.
